UNITED STATES PATENT OFFICE.

JAMES FRYE, OF INDIAN HEAD, MARYLAND.

BELT-GUIDE AND SUSPENDER-SUPPORT.

1,317,570.

Specification of Letters Patent. Patented Sept. 30, 1919.

Application filed May 19, 1919. Serial No. 298,219.

To all whom it may concern:

Be it known that I, JAMES FRYE, a citizen of the United States, and a resident of Indian Head, in the county of Charles 5 and State of Maryland, have invented certain new and useful Improvements in Belt-Guides and Suspender-Supports, of which the following is a specification.

This invention is an improved belt guide 10 and suspender support, and one of the principal objects thereof is to provide a combined belt guide and suspender support, serving the double function of properly guiding and holding the belt and of providing means on which the suspender may 15 be engaged, thereby doing away with the use of buttons.

Another object of the invention is to provide a guide and support of this nature 20 which is made of wire and which may be readily attached without the use of thread and without the use of any special tools or instruments.

A further object of the invention is to 25 provide an improved belt guide and suspender support which will be exceedingly simple, durable, efficient in operation and inexpensive to manufacture.

With these and other objects in view, 30 which will become apparent as the description proceeds, the invention resides in the construction, combination and arrangement of parts hereinafter more fully described and claimed, and illustrated in the accompanying drawings in which like characters 35 of reference indicate like parts throughout the several figures of which:

Figure 1 represents a view in perspective 40 of a portion of a pair of trousers around the belt line, showing the first step in securing the support and guide in place.

Fig. 2 represents a perspective view showing the completed device in operation.

Fig. 3 represents an elevational view of 45 the guide and support removed.

Referring more particularly to the drawing 5 indicates a fragment of garment around the belt line, and 6 indicates a fragment of the belt. The guide is formed of a 50 piece of suitable wire over-turned upon itself at one end as at 7, and at its other end formed into a hook or eye 8, which may have a restricted throat or entrance.

In attaching the device, the garment 5, 55 is provided with two openings at 9 and 10

respectively, one above the other. The wire may be attached in place in a number of different ways, one of which I will describe as follows. The wire is passed through the lower opening 10 from the inside of the 60 garment, the end 7 leading. At a point spaced from the eye end of the wire, the wire is bent upwardly to form the arm 11, the eye or hook 8 being arranged substantially at right angles to the plane of the 65 garment at that point. The remaining portion of the wire is then bent upwardly and thus a bend 12 passing through the opening 10 is formed. The wire is then passed inwardly through the opening 9 as indicated 70 in Fig. 1, a guide member 13, through which the belt 6 may be passed, thus being formed. Then the wire is bent down forming a bend at 14 and then passes into the opening 9; it is then passed through the hook or eye 75 8, and returned upon itself, thus forming a bend 15 engaged in the eye; then passing upwardly it is then again returned outwardly through the opening 9 and bent down forming a bow 16, which passes 80 through the opening 9, the free end of the wire depending in spaced relation to the guide 13, as at 17. This end 17 is spaced from the surface of the garment a distance 85 slightly beyond the point at which the guide 13 is spaced therefrom and thus forms a hook on which the button-hole of the suspender tab 18 may be engaged as indicated in Fig. 2. The returned end 7 will prevent abrasions of the material of the garment during 90 the process of fastening the device and it will also prevent abrasions of the suspender support. After the device has been attached to the garment the belt 6 may be passed through the guide member 13, and the suspender support engaged over the 95 hook 17. It will be seen that the guide may be used to the exclusion of the suspender support or the suspender support may be used to the exclusion of the guide. However, when they are both in use it will be noted that the suspender support serves to maintain the belt in proper position and prevent sagging of the latter. It will further be noted that the bow 16 is made on the 100 arc of a circle slightly greater than the bow 14 and these arcs intersect and overlap each other. Therefore when the suspender tab 18 is engaged on the hook 17 and moved up, it will be wedged between the hook and the 105 110

belt guide member 13, and thereby accidental displacement of the tab from the hook will be prevented.

It will be noted that when in final position the device comprises a closed loop comprising the guide member 13, the end portion 11, and the bowed portions 14 and 12, which closed loop passes through the two openings in the garment. The hook comprises the bow 16 and the end portion 17, and passes through the upper opening 9, and is offset from the guide in the manner set forth.

It will be noted that the device may be readily attached to the garment by any one without the use of needle or thread and without the use of any special tools, and that it does away with the necessity of providing garments with separate belt guide and suspender supporting means. It further does away with the use of buttons in supporting suspenders and in this connection it will be noted that no buttons are used for supporting the device or securing it in place.

It will, of course, be understood that any desired number of the devices may be attached to any one garment.

Although I have described the preferred embodiment of my invention, I may desire to make such changes in the construction, combination and arrangement of parts thereof, as do not depart from the spirit of the invention and the scope of the appended claims.

I claim:—

1. A combined belt guide and suspender support formed of a piece of wire having a hook provided at one end and being doubled upon itself at the other end, said wire being bent to form a closed loop and a supporting hook offset from the loop, the portion of the wire connecting the loop and supporting hook being passed through the hooked end of the wire.

2. A combined belt guide and suspender support formed of a length of wire having a hook at one end, said wire forming a

closed loop and a supporting hook offset laterally from the loop, the free end of the hook being also spaced from the adjacent side of the loop, the portion of the wire connecting the supporting hook and loop being engaged through the hook at the end of the wire.

3. A combined belt guide and suspender support made from a single length of wire and comprising an elongated closed loop, a supporting hook offset from the upper portion of the loop and in parallel relation thereto, the free end of the supporting hook being spaced from the adjacent side of the loop.

4. A combined belt guide and suspender support comprising a length of wire bent to form an elongated closed loop and an offset supporting hook, said hook spaced longitudinally from the loop and disposed in a plane parallel therewith.

5. The combination with a garment having spaced vertically aligned openings, of a guide and support including an elongated closed loop engaging through both the openings and a hook member passing through the upper one of said openings and extending downwardly in spaced relation to one side of the closed loop.

6. The combination with a garment having vertically aligned spaced openings of a combined guide and support comprising a closed loop engaging through the openings and a hook passing through one of the openings and providing a free end arranged in spaced relation longitudinally and parallel relation laterally with one side of the closed loop.

7. A device of the class described including an elongated closed loop and a hook member extending outwardly therefrom having its free end arranged in spaced parallel relation to one side of the loop, said hook disposed in a parallel plane laterally of the loop.

JAMES FRYE.
